LATCH MECHANISM FOR EXPLOSIVELY ACTUATED TOOL

Wilber J. Cranston, Milwaukie, Oreg., assignor to Omark Industries, Inc., Portland, Oreg., a corporation of Oregon

Application December 9, 1957, Serial No. 701,635

7 Claims. (Cl. 1—44.5)

This invention relates to a latch mechanism for an explosively actuated tool and more particularly to a latch mechanism for a tool of the type in which a handle portion is pivotally connected to a barrel portion so that the two portions of the tool may be pivoted with respect to each other between an open condition of the tool and a closed condition, the improved latch mechanism of the present invention reducing wear and damage to the engaging portions of the latch.

In several types of commercial explosively actuated tools, the handle portion of the tool is pivotally secured to the barrel portion thereof in order to enable such portions of the tool to be pivoted relative to each other from a closed condition of the tool in which the tool may be fired to an open condition in which the tool may be loaded and then back to a closed condition. In certain types of such tools, the tool is latched in closed condition by latch elements engaged by a forward movement of the handle portion of the tool relative to the barrel portion as the two portions of the tool approach closed condition of the tool. The forward motion of the handle portion relative to the barrel portion is produced by a spring urging the two portions of the tool toward each other and during the final closing movement of the tool, the latch elements are in contact with each other during relative lateral movement of such latch elements and such elements are subject to substantial wear when the tool is repeatedly opened and closed by workmen using the tool. Also, the engaging portions of the latch mechanism are subjected to impact when the tool is rapidly closed. In the particular tool disclosed in the present application, one of the latch engaging elements is a relatively thin rearwardly extending member which may be bent by such impacts so that the latch no longer functions.

In accordance with the present invention, the latch elements are held out of contact with each other until the two portions of the tool are brought into axial alignment during closing of the tool. Thus a member slidable in the barrel portion of the tool is held in a rearward position to which it is moved during opening of the tool. Upon such rearward movement of the slidable member, a plunger carried by such member is spring pressed outwardly to engage the housing of the barrel portion of the tool so as to prevent forward motion of such member until the plunger is depressed inwardly into the slidable member. Such plunger is depressed inwardly by an element carried by the handle portion of the tool so that the plunger is moved out of engagement with the housing of the barrel portion of the tool only when the handle portion reaches alignment with the barrel portion of the tool. This releases the member slidable in the barrel portion of the tool so that it can be carried forwardly by the spring referred to to carry the latch elements into engagement with each other. Such forward movement cannot, however, be produced until the handle portion of the tool is in axial alignment with the barrel portion. This prevents engagement between the latching elements until the pivotal movement between the two

portions of the tool to the closed condition of the tool has been completed. The result is the prevention of wear of the engaging surfaces of the latch elements and the prevention of bending of a latch element out of operative position.

It is therefore an object of the present invention to provide an improved latch mechanism for holding in closed condition an explosively actuated tool having the barrel portion and handle portion thereof pivotally connected to each other to provide for moving such portions relative to each other from an open condition of the tool to a closed condition of the tool.

Another object of the invention is to provide an improved latch mechanism for an explosively actuated tool having a handle portion pivotally connected to a barrel portion in which the contacting portions of the latch mechanism are maintained out of engagement during relative pivotal motion of such handle and barrel portions of the tool during closing of the tool until the handle portion has been brought into axial alignment with the barrel portion.

A still further object of the invention is to provide a latch mechanism for an explosively actuated tool having a barrel portion and a handle portion pivotally secured to each other to provide for opening and closing the tool and movable longitudinally with respect to each other between a latch engaging and a latch disengaging position in which the latch elements are maintained out of contact until the two portions of the tool reach axial alignment with each other during a tool closing operation in order to prevent damage to latch elements.

Other objects and advantages of the invention will appear in the following description of a preferred embodiment shown in the attached drawings of which:

Fig. 1 is a side elevation of a tool in accordance with the present invention with parts broken away to show the engaging portions of the latch elements;

Fig. 2 is a plan view of the tool with portions broken away to show internal structure;

Fig. 3 is a side elevation of the tool showing the opposite side from that shown in Fig. 1 with the barrel and breech block and the pivot therebetween shown in dotted lines;

Fig. 4 is a fragmentary plan view of the tool with the muzzle of the tool oriented in the same direction as in Fig. 3 and with parts broken away to show the latch structure; and

Fig. 5 is a view similar to Fig. 4 with the handle portion of the tool partially pivoted with respect to the barrel portion toward the opened condition of the tool.

Referring more particularly to the drawings, the tool shown therein has a barrel portion 10 and a handle portion 12. The barrel portion 10 includes a rubber covered barrel housing sleeve 16 and a barrel block sleeve 20, which together form a barrel housing. The barrel block sleeve 20 has a ring portion 22 at its front end surrounding and suitably secured to the rear end of the barrel housing sleeve 16 and also has rearwardly extending side portion 24 on one side thereof, forming one latch element of the latch mechanism as described in more detail below. The barrel block sleeve also has a shorter rearwardly extending side portion 26 on its other side which forms part of the mechanism for holding the latch elements out of contact until the two portions of the tool are in axial alignment.

The barrel portion 10 of the tool also includes a barrel 28 having its rear end secured in a barrel block 30 and its front end extending forwardly through the barrel housing sleeve 16. The barrel block 30 has flat upper and lower surfaces, as indicated by the dotted lines in Fig. 3, but has its side portions extending to and fitting the internal surfaces of the side portions 24 and 26 of the barrel block

sleeve 20, as indicated in Figs. 4 and 5. The barrel block 30 is urged toward the front or muzzle end of the tool by a compression spring 32 (Figs. 2 and 5) surrounding the barrel 28 and having its rearward end engaging against an inwardly directed flange 34 on the barrel housing sleeve 16 and its forward end engaging the rearward end of a barrel sleeve 36 secured to the barrel 28. Since the barrel block 30 is secured to the barrel 28, it is apparent that the spring 32 will urge the barrel block 30 forwardly against the rear end of the barrel housing sleeve 16.

The handle portion 12 of the tool includes a breech block 38, the rear portion of which is shown in Figs. 4 and 5 in horizontal section. Such breech block 38 is in the form of a U-shaped yoke, as indicated by the dotted lines in Fig. 3, and has forwardly extending leg portions above and below the barrel block 30 and in contact therewith, the lower one 40 of such leg portions being shown in plan in Fig. 5. The breech block 38 is pivotally connected to the barrel block 30 by means of a pivot pin 42, shown in Figs. 4 and 5 and in dotted lines in Fig. 3. The pivot pin extends vertically through the barrel block 30 into the legs 40 of the breech block and is spaced laterally from the axis of the barrel 28. The pivot pin 42 extends at right angles to the axis of the barrel 28 and has a cut away portion to clear the barrel. The breech block 38 is covered by a breech block sleeve or action housing sleeve 44 which in conjunction with a handle member 46 provides an action housing. The details of a suitable action by which a cartridge positioned in a breech plug 48 in the rear end of the barrel 28 is fired are disclosed in the copending application of Robert C. Kvavle, Serial No. 692,711, filed October 28, 1957, such details being unnecessary for an understanding of the present invention. In common with known types of explosively actuated tools, a spring urged firing pin (not shown) is released by a trigger 50 of the tool. The purpose of the member 52, shown in Figs. 4 and 5 as extending rearwardly from a portion of the barrel block 30 parallel to the barrel 28, is to remove a spent cartridge from the breech plug 48 after such breech plug has been removed from the barrel 28 as disclosed in more detail in the copending application of Robert C. Kvavle, Serial No. 692,758, filed October 28, 1957.

As shown in Fig. 4, the rearwardly extending latch element 24 of the breech block sleeve 20 fits in a notch in the action housing sleeve 44 and has at its rear end an axially extending inner latch portion 54 which extends under a corresponding outer axially extending latch portion 56 of the action housing sleeve 44, the latter mentioned portion providing the other latch element of the tool. In the position of the parts shown in Fig. 4, the two latch portions 54 and 56 interlock so as to prevent pivoting of the handle portion 12 of the tool toward an open position of the tool about the pivot pin 42. By grasping the handle member 46 of the tool with one hand and the barrel housing sleeve 16 with the other hand, the handle portion 12 of the tool can be pulled rearwardly of the tool with respect to the barrel housing, including the barrel housing sleeve 16 and barrel block sleeve 20, to disengage the latch portion 56 of the action housing sleeve 44 from the latch portion 54 of the barrel block sleeve 24. The handle portion 12 of the tool may then be pivoted about the pivot pin 42 from the position shown in Fig. 4 to the position shown in Fig. 5. The forward corner 58 of the yoke portions 40 of the breech block 38 engages the rear surface of the barrel housing sleeve 16, as shown in Fig. 5, to cam the assembly into the tool rearwardly with respect to the barrel housing sleeve 16 and the barrel block sleeve 20 to the position shown in Fig. 5.

A spring pressed plunger 60 is positioned in a laterally extending bore 62 in the barrel block 30 and, as shown in Fig. 4, is held in depressed position against the action of the spring 64 by both the rearwardly extending side

portion 26 of the barrel block sleeve 20 and a portion 66 of the action housing sleeve 44. That is to say, the action housing sleeve 44 is notched to fit around the rearwardly extending side portion 26 of the barrel block sleeve and it is the portion 66 of the action housing sleeve which is adjacent the rearward end of the side portion 26 of the barrel housing sleeve 20 which also holds the plunger 60 in the position shown in Fig. 4. When the handle portion 12 of the tool is moved rearwardly with respect to the barrel block sleeve 20 and then pivoted toward the position shown in Fig. 5 so as to be moved further rearwardly by the camming action of the corner 58 of the breech block 38 engaging the rear surface of the barrel housing sleeve 16, the plunger 60 clears the rearward end of the side portion 26 of the barrel block sleeve and is moved outwardly to the position shown in Fig. 5 by the spring 64. The plunger 60 is held against further movement outward by a pin 68 carried in the barrel block 30 and engaging in a recess 70 in one side of the plunger. The other side of the plunger also has a recess for clearing the end of the cartridge removing member 52. Engagement of the plunger 60 behind the end of the side portion 26 of the barrel block sleeve 20 holds the barrel block 30 rearwardly with respect to the barrel block sleeve and in the position shown in Fig. 5. The handle portion 12 may then be pivoted further to fully open position of the tool or may be pivoted back toward closed position of the tool while the barrel block 30 is held in its rearward position.

When the handle portion 12 is pivoted toward the closed tool condition shown in Fig. 4, the latch portion 56 of the action housing sleeve 44 clears the barrel block, as shown by the dotted line 72, and also clears the latch portion 54 of the latch element 24 of the barrel block sleeve 20. The portion 66 of the action housing sleeve 44 comes into contact with the plunger 60 as the handle portion 12 of the tool approaches axial alignment with the barrel portion 10 and as it comes into alignment, the plunger 60 is depressed sufficient that it clears the end of the side portion 26 of the barrel block sleeve 20, such that the spring 32 may return the barrel block 30 forwardly of the tool and into contact with the rear end of the barrel housing sleeve 16. This moves the latch portion 56 of the action housing sleeve 44 into engagement with the latch portion 54 of the barrel block sleeve 20 to latch the tool in closed condition. It will be noted, however, that there is no contact between the latch portions of the handle portion of the gun and the barrel portion of the gun until the handle and barrel portions are in axial alignment. Thus there is no tendency to bend the rearwardly extending side portion or latch element 24 of the barrel block sleeve out of latch engaging position. Also wearing of the latching portions of the two portions of the gun because of relative lateral motion of such parts when in engagement with each other is eliminated.

The operation of the latch mechanism of the present invention should be apparent from the above description. When the tool is in the tool closed condition shown in Figs. 1 to 4, inclusive, it can be employed to fire a stud 60 into a work surface as is well known in the art. The handle portion of the tool may then be pivoted to the tool opened position of Fig. 4 by pulling the handle member 46 rearwardly with respect to the barrel housing sleeve 16 and barrel block sleeve 20 to release the latching portion 56 of the action housing sleeve 44 from the latching portion 54 of the barrel block sleeve 20. This carries the barrel block 30 rearwardly with respect to the barrel housing sleeve 16 against the force of the spring 32. The pull exerted on the handle portion 46 with respect to the barrel housing sleeve will ordinarily carry the barrel block 30 sufficiently rearwardly with respect to the barrel block sleeve 20 that the plunger 60 will snap out of its depressed position, shown in Fig. 4, behind the end of the side portion 26 of the barrel block housing as soon as the handle portion of the tool is pivoted toward tool

opened position. In any event, when the handle portion has been pulled sufficiently rearwardly to cause the latching portion 56 of the action housing sleeve 44 to clear the latching portion 54 of the barrel block sleeve 20, the handle portion 12 of the gun may be pivoted to the position shown in Fig. 5 and the camming action of the corner 58 of the yoke leg portions 40 of the breech block 38 against the rear surface of the barrel housing sleeve 16 will move the barrel block 30 sufficiently rearwardly to cause the plunger 60 to clear the end of the side portion 26 of the barrel block sleeve 20. Such plunger thus assumes the position shown in Fig. 5 and the continued pivoting of the handle portion 12 of the tool will cause the corners 58 of the yoke portions 40 of the breech block to disengage the rear surface of the barrel housing sleeve 16. The barrel block 30 will, however, be maintained in its rearward position by the plunger 60 engaged against the rear end of the side portion 26 of the barrel block sleeve.

With the tool in its complete open position, a spent cartridge in the breech plug 48 may be removed therefrom by removing the breech plug from the end of the barrel 28 and sliding it onto the cartridge removing member 52. A stud may then be inserted into the barrel through the breech end thereof and the breech plug 48 may then be replaced in the barrel. A blank cartridge may then be inserted into the breech block after which the tool may be closed by pivoting the handle portion 12 about the pivot pin 42 with respect to the barrel portion 10 toward the closed tool position shown in Fig. 4. The latch portion 56 of the action housing 44 clears the end of the barrel block 30 and the latching portion 54 of the barrel block sleeve and as the handle portion 12 approaches axial alignment with the barrel portion 10, the portion 66 of the action housing sleeve 44 engages the end of the plunger 60 to depress the same. The plunger becomes fully depressed when the two portions of the tool reach axial alignment and this allows the barrel block 30 to be moved forwardly by the spring 32 to carry the breech block 38 forward along with the action housing sleeve 44, thus causing the latch portion 56 thereof to engage the latch portion 54 of the barrel sleeve 20. Such engagement is by an axial reciprocation motion only, thus avoiding any contact between the latching portions of the two sleeves during relative lateral motion thereof. As explained above, this prevents the bending of the latching portions and undue wear thereon.

While I have disclosed a preferred embodiment of my invention, it is understood that the details thereof may be varied and that the scope of the invention is to be determined by the following claims.

I claim:

1. In an explosively actuated tool having a barrel portion, a handle portion movable longitudinally of said barrel portion, resilient means urging said handle portion forwardly relative to said barrel portion, said handle portion being pivoted to said barrel portion to provide for pivotally moving said portions relative to each other between a closed condition of said tool in which said portions are in axial alignment with each other and an opened condition exposing the rear end of said barrel portion, a latch mechanism for holding said tool in said closed condition comprising latch elements on said portions engaged by forward movement of said handle portion relative to said barrel portion by said resilient means when said tool is in closed position and releasable by moving said handle portion rearwardly of said barrel portion against the force of said resilient means, and means rendered operative by relative pivotal movement of said portions from said closed condition toward said opened condition for holding said handle portion in a predetermined rearward position relative to said barrel portion preventing engagement of said latch elements until said portions are pivotally moved into axial alignment with each other.

2. In an explosively actuated tool having a barrel por-

tion including a member movable longitudinally of said barrel portion, resilient means urging said member toward the forward end of said barrel portion and a handle portion pivoted to said member to provide for pivotally moving said portions relative to each other between a closed condition of said tool in which said portions are in axial alignment with each other and an opened condition exposing the rear end of said barrel portion, a latch mechanism for holding said tool in said closed condition comprising latch elements on said portions engaged by forward movement of said handle portion relative to said barrel portion by said resilient means when said tool is in closed position and releasable by moving said handle portion and said member rearwardly of said barrel portion against the force of said resilient means, and means rendered operative by relative pivotal movement of said portions from said closed condition toward said opened condition for holding said handle portion in a predetermined rearward position relative to said barrel portion to prevent engagement of said latch elements until said portions are pivotally moved into axial alignment with each other.

3. In an explosively actuated tool having a barrel portion including a barrel, a barrel housing, a member movable longitudinally of said barrel housing, resilient means urging said member toward the forward end of said barrel housing and a handle portion pivoted to said member to provide for pivotally moving said portions relative to each other between a closed condition of said tool in which said portions are in axial alignment with each other and an opened condition exposing the rear end of said barrel, said handle portion including an action housing, a latch mechanism for holding said tool in said closed condition comprising latch elements on said housings engaged by forward movement of said handle portion relative to said barrel portion by said resilient means when said tool is in closed position and releasable by moving said handle portion and said member rearwardly of said housing against the force of said resilient means, and holding means rendered operative by relative pivotal movement of said portions from said closed condition toward said opened condition for holding said member in a predetermined rearward position relative to said barrel portion to prevent engagement of said latch elements until said portions are pivotally moved into axial alignment with each other, said handle portion having a part engaging said holding means to release said holding means when said portions are moved into said axial alignment.

4. In an explosively actuated tool having a barrel portion including a barrel, a barrel housing and a first member movable longitudinally of said barrel portion and resiliently urged toward the front end of said barrel housing and a handle portion including a second member pivoted to said first member for pivotal movement about an axis extending at right angles to said barrel to provide for pivotally moving said portions relative to each other between a closed condition of said tool in which said portions are in axial alignment with each other and an opened condition exposing the rear end of said barrel, a latch element carried by said handle portion and engaging said housing to hold said tool in closed position when said first member is in a forward position relative to said housing and releasable by moving said handle portion and said members rearwardly of said housing and means rendered operative by relative pivotal movement of said portions from said closed condition toward said opened condition for holding said first member in a predetermined rearward position relative to said housing to prevent engagement of said latch elements until said portions are pivotally moved into alignment with each other.

5. In an explosively actuated tool having a barrel portion including a barrel, a barrel housing and a first member movable longitudinally of said barrel portion and

resiliently urged toward the front end of said barrel housing and a handle portion including an action housing and second member pivoted to said first member for pivotal movement about an axis extending at right angles to said barrel to provide for pivotally moving said portions relative to each other between a closed condition of said tool in which said portions are in axial alignment with each other and an opened condition exposing the rear end of said barrel, a latch element carried by said action housing and engaging a latch element on said barrel housing when said first member is in a forward position relative to said barrel housing to hold said tool in closed position and releasable by moving said handle portion and said members rearwardly of said barrel housing and holding means rendered operative by relative pivotal movement of said portions from said closed condition toward said opened condition for holding said first member in a predetermined rearward position relative to said barrel housing to prevent engagement of said latch elements until said portions are pivotally moved into alignment with each other, said action housing having a part engaging said holding means to release said holding means when said portions are moved into axial alignment.

6. In an explosively actuated tool having a barrel portion including a barrel, a barrel housing and a member movable longitudinally of said barrel portion and resiliently urged toward the front end of said barrel housing and a handle portion including a second member pivoted to said first member for pivotal movement about an axis extending at right angles to said barrel to provide for pivotally moving said portions relative to each other between a closed condition of said tool in which said portions are in axial alignment with each other and an opened condition exposing the rear end of said barrel, a latch mechanism comprising latch elements on said portions engaged with each other by forward movement of said handle portion relative to said housing when said tool is in closed position and releasable by moving said handle portion and said first member rearwardly of said housing, a holding member carried by said first member and movable outwardly thereof to engage said housing to hold said first member in a predetermined rearward position relative to said housing when said first member

is moved rearwardly of said housing and said portions are pivotally moved relative to each other from said closed condition toward said opened condition, said handle portion having a part engaging said holding member to move it out of engagement with said housing when said portions are pivoted toward closed position and brought into axial alignment with each other so that engagement of said latch elements is prevented until said portions are in axial alignment and engagement of said elements is by relative movement axially of said tool.

7. In an explosively actuated tool having a barrel portion including a barrel, a barrel housing and a member movable longitudinally of said barrel portion and resiliently urged toward the front end of said barrel housing and a handle portion including an action housing and a second member secured in said action housing and pivoted to said first member for pivotal movement about an axis extending at right angles to said barrel to provide for pivotally moving said portions relative to each other between a closed condition of said tool in which said portions are in axial alignment with each other and an opened condition exposing the rear end of said barrel, a latch mechanism comprising latch elements carried by said housings and engaged by forward movement of said handle portion relative to said barrel housing when said tool is in closed position and releasable by moving said handle portion and said first member rearwardly of said barrel housing, a plunger carried by said first member and movable outwardly thereof to engage said barrel housing to hold said first member in a predetermined rearward position relative to said barrel housing when said first member is moved rearwardly of said barrel housing and said portions are pivotally moved relative to each other from said closed condition toward said opened condition, said action housing having a part engaging said plunger to move it out of engagement with said barrel housing when said portions are pivoted toward closed position and brought into axial alignment with each other so that engagement of said latch elements is prevented until said portions are in axial alignment and engagement of said elements is by relative motion axially of said tool.
